DESIGN.

A. M. MALONE,

SEALING TAPE.

APPLICATION FILED OCT. 3, 1921.

60,962.

Patented May 16, 1922.

Inventor:

Annie M. Malone,
by Ripley Kingsland
Her Attorney's.

UNITED STATES PATENT OFFICE.

ANNIE M. MALONE, OF ST. LOUIS, MISSOURI.

DESIGN FOR A SEALING TAPE.

60,962.

Specification for Design.

Patented May 16, 1922.

Application filed October 3, 1921. Serial No. 505,188. Term of patent 14 years.

To all whom it may concern:

Be it known that I, ANNIE M. MALONE, a citizen of the United States, and a resident of the city of St. Louis and State of Missouri, have invented a new, original, and ornamental Design for a Sealing Tape, of which the following is a specification, reference being had to the accompanying drawing, forming part thereof.

The drawing shows my new design.

I claim:

The ornamental design for a sealing tape, as shown.

ANNIE M. MALONE.
